FIG 2

To all whom it may concern:

Be it known that we, **Raymond Spilman** and **Anthony R. Morrow**, citizens of the United States, residing, respectively, at Bronxville, in the county of Westchester and State of New York, and Newton, in the county of Sussex and State of New Jersey, have invented a new, original, and ornamental Design for a Merchandising Machine Cabinet, of which the following is a specification, reference being had to the accompanying drawing, forming a part thereof.

Figure 1 is a perspective view of a merchandising machine cabinet, showing our new design.

Figure 2 is a side elevation of the merchandising machine cabinet shown in Figure 1.

The side of the cabinet not shown in the drawing is

the same in appearance as the side shown. The rear of the cabinet is plain.

We claim:

The ornamental design for a merchandising machine cabinet, substantially as shown and described.
